United States Patent Office

Des. 187,807
Patented May 3, 1960

187,807

FLOWER POT

John L. Manfredi, Wyckoff, N.J.

Application December 2, 1958, Serial No. 53,617

Term of patent 14 years

(Cl. D35—3)

Fig. 1 is a top perspective view of a flower pot showing my new design;

Fig. 2 is a bottom plan view thereof; and

Fig. 3 is a fragmentary vertical cross-sectional view taken on line 3—3 of Fig. 1.

I claim:

The ornamental design for a flower pot, as shown.
